UNITED STATES PATENT OFFICE.

JOHN M. KEEFE, OF CAMDEN, NEW JERSEY.

DESIGN FOR A BRUSH.

SPECIFICATION forming part of Design No. 26,215, dated October 27, 1896.

Application filed August 29, 1896. Serial No. 604,387. Term of patent 7 years.

To all whom it may concern:

Be it known that I, JOHN M. KEEFE, a citizen of the United States, residing in the city and county of Camden, in the State of New Jersey, have invented and produced a new and original Design for Stair or Furniture Brushes, of which the following is a specification, reference being had to the accompanying drawing, illustrating the same.

10 The drawing shows a perspective view of a brush embodying my design.

Referring now to the drawing, A is a series of bunches of bristles, tampico or West Indies fiber or the like, mounted on a backing B of rectangular outline and forming a brush, *per se*, the outer or free ends of the brush at the two ends B^X B^X of the backing B spreading at an angle with said backing to extend beyond the length of the latter, as at C. A handle D is attached to the backing B on its upper or free side midway its length and ex-

tending at right angles therewith, and on the outer end of said handle D is a brush E, of round or circular outline as to its central body portion, as at E^X, and tapering in one direction toward the handle D, as at E^{XX}, and likewise to a point in the opposite direction toward its free end, as at E^{XXX}.

What I claim is—

The design for a brush herein shown and described, the same comprising a brush of rectangular outline, a handle at right angles therewith and a brush on the end of said handle round in outline and tapered from its center toward both ends, as set forth.

In testimony whereof I have hereunto signed my name this 3d day of December, A. D. 1895.

JOHN M. KEEFE.

In presence of—

WILLIAM J. KROSS,
WM. EARLY.
